METHOD OF MAKING INTAGLIO PRINTING PLATES

Charles P. Shaw, Detroit, Mich., assignor to Detroit Moulding Corporation, Detroit, Mich.

Application December 17, 1934, Serial No. 757,792

13 Claims. (Cl. 95—5.7)

The main objects of this invention are:

First, to provide an improved method of making intaglio printing plates which are especially well adapted for use in offset printing.

5 Second, to provide an improved method of reproducing wood grain effects by means of offset printing from photomechanical intaglio plates.

10 Third, to provide an improved intaglio printing plate which is especially well adapted for use in the reproduction of wood grain effects by offset printing.

15 Objects relating to details and economies of my invention will appear from the description to follow. The invention is defined and pointed out in the claims.

20 Certain steps of my method are illustrated in the accompanying drawing, in which:

Fig. 1 is a view in front elevation of the copy or subject to be reproduced.

25 Fig. 2 is a view in front elevation of the continuous tone negative of the subject.

Fig. 3 is an enlarged view in end elevation of the continuous tone negative and the positive arranged for contact exposure.

30 Fig. 4 is a view in front elevation of the continuous tone positive transparency.

Fig. 5 is a diagrammatic top plan view showing the apparatus arranged to carry out the fourth step of my method.

35 Fig. 6 is a greatly enlarged fragmentary plan view of the screen negative resulting from the high light exposure.

Fig. 7 is a similar view of the screen negative resulting from the middle tone exposure.

40 Fig. 8 is a similar view of the screen negative resulting from the shadow exposure.

45 Referring to the drawing, the subject 1 to be reproduced, in this case a natural wood grain effect, is first photographed to produce a continuous tone negative 2 which may be retouched as desired. This continuous tone negative is converted into a continuous tone positive 4 preferably on glass 5 to provide the continuous tone positive transparency 6. The positive transparency so obtained is intensified, retouched and corrected to bring out the desired tones and details.

50 I next place the transparency 6 in front of the camera 7, the face of the transparency or the side having the emulsion of the positive 4 facing the camera lens. The transparency 6 is lighted from the back by light reflected from the white reflector 8, the light originating in rays 9 from a light source not shown. The reflected light rays 10 from the reflector are diffused and broken up 55 relative to the light rays 9, and in addition, the

reflected light rays are somewhat diffused and refracted by the glass transparency 6, the refracted light rays being shown at 11.

The positive 4 on the transparency 6 is arranged to face the lens of the camera in order not to get too much refraction of light. On account of the light penetrating through the transparency and on account of the slight grain of the emulsion, I obtain a very much richer and more varied tone, as well as cleaner cut detail 10 than is obtainable by the usual method of lighting a photographic print by direct lighting. The old method of lighting has a tendency to bleach out the copy by a hard lighting effect, whereas my indirect method reserves all of the softness, 15 contrast and detail of the original. Where flat subjects are photographically copied in the foregoing manner, there is a decided gain in life and in tone values.

20 The camera is set for the exact size or less of the positive, and operates to concentrate the diffused light, and reproduces on the sensitized plate 12 sharp detail and a great variety of tone, in the same manner as when photographic copy is considerably reduced in size to bring out its 25 sharpness. A ruled screen 13 is placed in the camera to produce a screened negative 14 on the plate 12.

30 In making the screen negative 14, I use three definite exposure steps to bring out high lights, middle tones, and shadows. Very satisfactory results may be had by observing the following directions. To make the high light exposure, use an F16 stop, which is a fairly large aperture, for a period of three minutes. The next exposure may be for three and one-half minutes with an F32 stop or aperture, which is about one-half the size of the F16 stop. In the third and final exposure, a No. 15 stop may be used, the time of exposure being six minutes. A No. 15 stop is 40 about one-fourth the size of an F32 stop.

35 The first high light exposure produces practically a black and white negative 15, Fig. 6, the blacks 16 being solid except for occasional lights 17, and the high lights 18 being very pronounced. 45 This may be designated the first stage in the production of the screen negative. The middle tone exposure produces a second stage, Fig. 7, in which some of the blacks have been converted into middle tones 19 and some of the high light dots 20 have become smaller. In the third and last stage, Fig. 8, more of the blacks are changed to middle tones and more detail is injected into the black; the high light dots are small and the whole subject is grayer and less contrasting. 50 55

This insures softness and the correct difference in depth of the dots or pockets after etching.

The screen negative so produced is converted into a positive (not shown), a print of such positive being made on a metal plate (not shown) having a sensitized surface which is subsequently etched in a known manner. Since very little depth is required, the etching time is preferably short. The resulting intaglio printing plate is 10 divided into cells of greatly varying area, the depth of the cells being directly proportional to their area. Some of the cells are connected, while others are unconnected, this being clearly shown by Fig. 8, the black dots in this case 15 representing the cells.

My intaglio printing plate made in the foregoing manner is well adapted for offset printing owing to the great variety in the size of the cells which are adapted to carry the transfer ink. 20 The various high light, middle tone, and shadow cells are relatively small and thus prevent slurring in the final reproduction which is faithful to the original and very attractive in appearance.

I have illustrated and described my improvements in an embodiment which I have found very practical. I have not attempted to illustrate or describe other embodiments or adaptations as it is believed this disclosure will enable those skilled in the art to embody or adapt my 25 improvements as may be desired.

Although I have shown and described a certain specific embodiment of my invention, I am fully aware that many modifications thereof are possible. My invention is therefore not to be 30 restricted except insofar as is necessitated by the prior art and by the spirit of the appended claims.

Having thus described my invention, what I claim as new and desire to secure by Letters 40 Patent is:

1. The method of making an intaglio plate for offset printing, which comprises the steps of making a continuous tone negative of the subject, converting said continuous tone negative 45 into a positive transparency, modifying the tone and detail of said positive transparency, lighting the transparency by reflected light passing through the transparency and being diffused and refracted thereby, making a screen negative of 50 the transparency so lighted by exposure first with a fairly large stop for three minutes to bring out the high lights, then with a stop of one-half the size of the first for three and one-half minutes to bring out the middle tones, and 55 finally with a stop one-fourth the size of the second for six minutes to bring out the shadows, making a screen positive from the screen negative, and making an etched intaglio printing plate from said screen positive, the exposures and etching being controlled so that the depth of the 60 cells is directly proportional to their area.

2. The method of making an intaglio plate for offset printing, which comprises the steps of making a continuous tone negative of the subject, 65 converting said continuous tone negative into a positive transparency, lighting the transparency by reflected light passing through the transparency, making a screen negative of the transparency so lighted by exposure first with a fairly 70 large stop for three minutes to bring out the high lights, then with a stop of one-half the size of the first for three and one-half minutes to bring out the middle tones, and finally with a stop one-fourth the size of the second for six 75 minutes to bring out the shadows, making a

screen positive from the screen negative, and making an etched intaglio printing plate from said screen positive.

3. The method of making an intaglio plate for offset printing, which comprises the steps of 5 making a continuous tone negative of the subject, converting said continuous tone negative into a positive transparency, lighting the transparency by reflected light passing through the transparency and being diffused and refracted 10 thereby, making a screen negative of the transparency so lighted by successive exposures to bring out the high lights, middle tones, and shadows, making a screen positive from the screen negative, and making an etched intaglio 15 printing plate from said screen positive, the exposures and etching being controlled so that the depth of each cell is proportional to its area.

4. The method of making an intaglio plate for 20 offset printing, which comprises the steps of making a continuous tone negative of the subject, converting said continuous tone negative into a positive transparency, lighting the transparency by reflected light passing through the transparency and being diffused and refracted 25 thereby, making a screen negative of the transparency, making a screen positive from the screen negative, and making an intaglio printing plate from said screen positive.

5. The method of making an intaglio plate for 30 offset printing, which comprises the steps of making a continuous tone negative of the subject, converting said continuous tone negative into a positive transparency, modifying the tone 35 and detail of said positive transparency, making a screen negative of the transparency by successive exposures first with a fairly large stop for three minutes to bring out the high lights, then with a stop of one-half the size of the first for three and one-half minutes to bring out the middle tones, and finally with the stop one-fourth the size of the second for six minutes to bring out the shadows, making a screen positive from the screen negative, and making an etched intaglio printing plate from said screen positive, 45 the etching being controlled so that the depth of the cells is directly proportional to their area.

6. The method of making an intaglio plate for 50 offset printing, which comprises the steps of making a continuous tone negative of the subject, converting said continuous tone negative into a positive transparency, making a screen negative of the transparency by successive exposures with a fairly large stop for three minutes to bring out the high lights, then with a 55 stop of one-half the size of the first for three and one-half minutes to bring out the middle tones, and finally with a stop one-fourth the size of the second for six minutes to bring out the shadows, making a screen positive from the 60 screen negative, and making an intaglio printing plate from said screen positive.

7. The method of making intaglio printing plates, which comprises the steps of making a continuous tone positive transparency of the subject to be reproduced, lighting the transparency by reflected light with the emulsion of the positive transparency facing the lens of a camera, making a screen negative in said camera of the transparency so lighted, and making an etched 70 intaglio printing plate from said negative, said plate having cells of greatly varying area whose depth is directly proportional to their area.

8. The method of making intaglio printing plates, which comprises the steps of making a 75

- continuous tone positive transparency of the subject to the reproduced, lighting the transparency by reflected light passing therethrough with the emulsion of the positive transparency facing the 5 lens of a camera, making a screen negative in said camera of the transparency so lighted, and making an etched intaglio printing plate from said negative.
9. The method of making intaglio printing plates, which comprises the steps of making a continuous tone positive transparency of the subject to be reproduced, lighting the transparency by reflected light, making a screen negative in said camera of the transparency so lighted, and 15 making an etched intaglio printing plate from said negative.
10. The method of making intaglio printing plates, which comprises the steps of making a continuous tone positive transparency of the subject, making a screen negative of said transparency by successive exposures first with an F16 stop for three minutes to bring out the high 20 lights, then with an F32 stop for three and one-half minutes to bring out the middle tones, and then with a No. 15 stop for six minutes to bring out the shadows, and making an etched intaglio printing plate from said screen negative, the plate being provided with cells of greatly varying area whose depth is directly proportional to their area. 25
11. The method of making intaglio printing plates, which comprises the steps of making a continuous tone positive transparency of the subject, making a screen negative of said transparency by successive exposures first with an F16 30
- stop for three minutes to bring out the high lights, then with an F32 for three and one-half minutes to bring out the middle tones, and then with a No. 15 stop for six minutes to bring out the shadows, and making an etched intaglio 5 printing plate from said screen negative.
12. The method of making an intaglio plate for offset printing, which comprises the steps of making a continuous tone negative of the subject, converting said continuous tone negative 10 into a positive transparency, lighting the transparency by reflected light passing through the transparency, making a negative of the transparency so lighted by exposure first with a fairly large stop for three minutes to bring out the high 15 lights, then with a stop of one-half the size of the first for three and one-half minutes to bring out the middle tones, and finally with a stop one-fourth the size of the second for six minutes to bring out the shadows, making a positive from 20 said last named negative, and making an etched intaglio printing plate from said positive.
13. The method of making an intaglio plate for offset printing, which comprises the steps of making a continuous tone negative of the subject, converting said continuous tone negative 25 into a positive transparency, lighting the transparency by reflected light passing through the transparency and being diffused and refracted thereby, making a negative of the transparency, 30 making a positive from the negative, and making an intaglio printing plate from said positive.
